FEEDING OF LABELS, SHEETS, AND THE
LIKE FROM A STACK

Alfred German Rose, Gainsborough, England,
assignor to Rose Brothers (Gainsborough)
Limited, Gainsborough, England, a British
company

Application February 6, 1951, Serial No. 209,557
In Great Britain February 17, 1950

10 Claims. (Cl. 216—55)

1

This invention relates to the feeding of labels, sheets, or the like (hereinafter referred to as "labels") from a stack, and is particularly, though not exclusively, concerned with the feeding of labels in apparatus for labelling bottles or other containers (hereinafter referred to as "bottles").

In such apparatus, it is usual to extract the end label from a stack in a magazine by means of a pick-up member which may seize the label by suction or by means of gum applied to the face of the member, the stack being resiliently urged towards the mouth of the magazine where it is held against the pressure applied to the stack only by means of a series of pins or similar retaining members arranged around the periphery of the magazine and projecting inwardly by an amount sufficient to hold the stack but at the same time allowing the end label to be withdrawn by the pick-up member by deflecting the edges of the label past the pins. It is sometimes found, however, that substantial resistance to extraction of the label by the pick-up member is encountered, presumably by reason of a jamming action between the forward end of the stack and the retaining pins. It is with this difficulty that the present invention is concerned.

According to the present invention, labels are fed in succession from a magazine, in which a stack of labels are resiliently urged against a series of retaining members, by depressing the stack inwardly out of contact with the retaining members and, while the stack is so depressed, seizing the end label by a pick-up member and withdrawing at least one edge of the label from the magazine, the pick-up member then removing the label from the magazine. In this manner, the only resistance to extraction of the label is that offered by the deflection of the edge or edges of the label as it meets the retaining members. The label may be seized by suction or by gum applied to the operative face of the pick-up member.

In a preferred embodiment of the invention, the pick-up member is formed with suction openings and is divided along a line in its operative surface, the two portions being mounted for pivotal movement about an axis coincident with the dividing line, the adjacent edges of the two portions being suitably bevelled away from the operative surface to allow for the pivotal movement. With such a construction, the depression of the stack is brought about by the pick-up member itself, e. g., by moving the stack into engagement with the pick-up member, and while

2

the stack is so depressed, the two portions of the pick-up member are pivoted outwardly so as to deflect the two ends of the end label away from the stack, the portions of the pick-up member adjacent the pivotal axis serving to hold the stack in depressed position in the meantime. Upon retraction of the stack, therefore, the end label is extracted with little resistance from the retaining members.

10 The invention will now be described in greater detail with reference to the accompanying diagrammatic drawings, as applied to a machine for labelling bottles or other cylindrical articles.

In the drawings:

15 Figures 1 and 2 are an elevation and plan, respectively, of a bottle-labelling machine.

Figures 3 and 4 are an elevation and plan, respectively, of a portion of the machine, drawn to a larger scale.

20 Figure 5 is a plan of a detail of the machine showing the suction arrangement, and

Figure 6 is a section taken on the line 6—6 of Figure 5.

Briefly describing the machine with reference 25 to Figures 1 and 2, a common rotatable support 11 carries four suction pick-up members 12 and is mounted in a stationary pillar 13 secured to a base plate 14, the support 11 being intermittently rotated as described below. The support

30 11 carries each pick-up member 12 firstly into register with the end of a label stack 18, carried in a horizontal magazine 19, so as to seize a label by suction, then to an idle station where a further operation (e. g., a detecting operation) may be performed; then to a gumming station at which a layer of gum is applied to the label on the pick-up member; and finally to a labelling station at which a conveyor 21 is arranged to carry a succession of bottles 22, spaced by a worm 23, past the common support 11. At this station, the foremost bottle 22 is rolled across the label on the pick-up member for the time being at that station so as to cause the label to be pressed on to the bottle, the rolling action being performed by a driven belt 24 mounted on a pair of pulleys 26 and 27, the pulley 27 being resiliently urged towards the conveyor by a spring 28 acting on an arm 29 carrying the pulley 27. After the labeling operation, the bottles 22 are passed on to a delivery table 31.

45 The various mechanisms constituting the whole machine will now be described in greater detail.

50 Referring particularly to Figures 1 to 4, the

55 *Pick-up members and driving gear*

common support 11 consists of a lower plate 32 (driven in the manner described below), a supporting pillar 33 secured to the plate 32 and an upper plate 34 secured to a spider 36 formed on the pillar 33 by means of studs 37 serving also to space the plate 34 from the spider 36. The lower plate 32 is secured to a driving tube 35 mounted in bearings in the stationary pillar 13 and driven at its lower end by a Geneva mechanism 40, 45, the member 46 of which is driven from the shaft 86 by a shaft 50 and bevel gearing 55.

The four pick-up members 12 are similar in construction and operation, each having an operative facing 38 of polytetrafluoroethylene formed with suction openings 39, the facing 38 being divided along a line 41. Each part of the facing 38 is secured to an operating member 42 (43) pivotally mounted on the lower plate 32 and the upper plate 34 for movement about an axis coincident with the line 41. The operating member 42 (43) is formed with a suction chamber 44 (144) fed by a suction line 46 (47). The chambers 44 (144) in the members 42 (43) are covered by the two parts of the suction facing 38 so that suction is applied to the facing 38 from the two lines 46 and 47.

The members 42 (43) are each pivotally connected by a link 48 to a common arm 49 pivotally mounted on the spider 36, a cam roller 57 being freely mounted on a stud 52 serving to connect the two links 48 to the arm 49. The cam roller 51 is arranged to bear against the face of a cam 53 secured to a shaft 54 extending through the supporting pillar 33 and the driving tube 35, an operating arm 56 being secured to the lower end of the shaft 54. The arm 56 is connected by a link 57 to a pivoted arm 58 carrying a cam roller 59 arranged to bear against the face of a rotatable cam 61.

Suction connections

The suction lines 46 (47) of the four pick-up members 12, are supplied from a common port chamber constituted by the lower plate 32, a lower port member 62 and a dividing plate 63, the common port chamber being supplied from a main suction head 64. The various suction connections can best be seen from Figures 5 and 6. Thus, a main suction line 66 is connected to the suction head 64 in which is formed an arculate recess 67 from which suction is supplied through ports 68 and 69 in the lower member 62 and the dividing plate 63, respectively, to a transverse port 71 formed in the lower plate 32 and terminating in a port 72 to which is connected the suction line 46. Suction is also supplied from the recess 67 through a port 73 and a transverse port 74 in the lower member 62 to a port 76 in the plate 63 and a port 77 in the lower plate 32 (see Figure 5) to which is connected the suction line 47, the transverse ports 71 and 74 being separated by the plate 63.

Label magazine

The label stack 18 is carried in the magazine 19 which is slidably mounted in a slideway 78 mounted on the machine framework 80. The magazine 19 is caused to move towards and away from the pick up member 12 for the time being at the label feeding station by means of a two-armed pivoted lever 79, 81, the arm 79 being connected to the base of the magazine by a link 82 while the arm 81 carries a cam roller 83 arranged to bear against the face of a rotatable cam 84

secured to a shaft 86. The magazine 19 is provided with a movable pressure plate 87 arranged to push the stack of labels towards a series of pins 88 mounted in the forward end of the magazine. Pressure is applied to the plate 87 by means of a pair of weights 89 each attached to one end of a cable 91 arranged to pass over a pair of pulleys 92, the other end of the cable being attached to the plate 87. The plate 87 is formed with an extension 93 arranged to slide in the framework of the magazine 19 and provided with ratchet teeth 94 on its upper surface. A ratchet pawl 96 pivoted in the framework of the magazine 19 is arranged to engage the teeth 94 of the extension 93 to prevent rearward movement of the plate 87.

Gumming mechanism

At the gumming station a layer of gum is applied to the label on the pick-up member by a gum-applying roller 96 mounted in a forked arm 97 arranged to slide in a pivoted slideway 98. The roller 96 is supplied with gum from a gum bath 99 by an intermediate roller 101 and a main roller 102 rotatably mounted in the bath 99. The roller 102 is driven by chain and sprocket gearing 104 from a drive shaft 106, while the roller 96 is driven by gearing 107 from the roller 102. The intermediate roller 101 is carried by pairs of links 108 and 109 connecting the axis of the gum bath 99 with the axis of the roller 96, thus ensuring continuous engagement between the gearing 107. Sliding movement of the arm 97 is brought about by an eccentric 111 mounted on the shaft 106 and connected by a link 112 to the arm 97. The slideway 98 is pivoted on the shaft 106 and is caused to rock by means of a pivoted arm 113 connected to the slideway 98 by a link 114 and carrying a cam roller 116 arranged to bear against the face of a cam 117 mounted on the shaft 106. The shaft 106 is driven from the shaft 86 by a cross shaft 100 and bevel gearing 105. The shape of the cam 117 and its timed relationship with the eccentric 111 are such that the combined movements of the arm 97 and slideway 98 causes the roller 96 first to roll down the face of the label to apply gum thereto, and then move away from the pick-up member 12 before making its return movement.

Operation

From the above description of the apparatus, it will be clear that, while one label is being withdrawn from the stack 18, another is being gummed at the gumming station while a third is being transferred to the bottle 22 passing the labelling station.

The conveyor 21, worm 23, common support 11, label magazine 19 and gum bath 99 are all driven in timed relationship to ensure the delivery of a bottle at the labelling station for each movement of the support 11 and the simultaneous action of the label-feeding and gumming mechanisms. The speed of the belt 24 is such as to deliver the labelled bottles in spaced relationship.

Assuming the apparatus to be in continuous motion, the action of one pick-up member 12 will be described from the moment it reaches the label-feeding station. As the member 12 comes to rest under the action of the Geneva mechanism 40, 45, the magazine 19 is moved by the cam 84 to press the stack 18 against the facing 38 of the member 12, and to press the end of the stack 18 away from the retaining pins 88. During this action, suction is applied to the cham-

bers 44 and 144 through the lines 46 and 47 from the arcuate recess 67 in the suction head 64 so as to cause the facing 38 to seize the end label by suction.

While the stack 18 is thus depressed out of contact with the pins 88 (see Figure 4), the shaft 54 is partially rotated by the arm 56 under the influence of the rotating cam 61 so as to cause a depression 121 in the cam 53 to move into register with the cam roller 51, thus allowing the arm 49 to pivot inwardly under the action of a spring 122. Such movement of the arm 49, through the links 48, causes the two operating members 42 and 43 to pivot about the line 41, thus causing the two parts of the facing 38 to withdraw opposite edges of the end label in the stack clear of the pins 88. It will thus be seen that the only resistance to extraction of the label from the stack is that offered by the deflection of the opposite edges of the label as they meet the pins 88.

With the label thus deflected by the facing 38, the magazine 19 is withdrawn clear of the facing 38, and the support 11 rotated to an idle station (where a detecting operation may be performed on the label if desired), the cam roller 51 riding on to the outer surface of the cam 53 during such movement to cause the two parts of the facing 38 to return to their normal positions. The cam 53 is also returned to its normal position during this movement.

The support 11 is then moved to carry the pick-up member 12 to the gumming station where the roller 96, operating in the manner described above, applies a layer of gum to the label on the facing 38. A further movement of the support 11 then carries the pick-up member 12 to the labelling station where a bottle 22 is rolled across the facing 38 by the pressure of the belt 24 to cause the bottle to pick the label off the facing 38.

Suction is applied to the chamber 144 continuously from the label-feeding station to the labelling station from the arcuate recess 67, but as the pick-up member closely approaches the labelling station, the port 68 moves out of the influence of the recess 67 and into register with a port 123 in the suction head 64 to which air under pressure is supplied from a line 124. In this manner, while the label is still held to the facing 38 by the suction applied to the chamber 144, air under pressure passes from the port 123 through the ports 68, 69 and 71 to the chamber 44, thus assisting the removal of the label from the facing 38 by the bottle 22.

I claim:

1. Apparatus for feeding labels from a stack, comprising a magazine in which the stack is resiliently urged against a series of retaining members, a pick-up member adapted to seize the end label in the stack, said pick-up member being divided along a straight line in its operative surface, means for causing a relative movement between the pick-up member and the magazine so as to cause engagement between the pick-up member and the stack by which the stack is depressed inwardly out of contact with the retaining members, means for pivoting at least one portion of the pick-up member about an axis coincident with said line after the seizing action and while the stack is so depressed so as to withdraw at least one edge of the label from the magazine, and means for causing the pick-up member subsequently to withdraw the label from the magazine.

2. Apparatus as in claim 1, comprising suction apertures in the operative face of the pick-up member, and means for applying suction to the apertures so as to cause the pick-up member to seize the label by suction.

3. Apparatus as in claim 2, wherein both portions of the pick-up member are adapted to pivot simultaneously about said axis.

4. Apparatus as in claim 1 wherein the pick-up member is adapted to remain stationary during the depression of the stack, the relative movement being brought about by moving the magazine toward the pick-up member, and wherein both portions of the pick-up member are adapted to pivot simultaneously about said axis.

5. Method of feeding labels in succession from a magazine in which a stack of labels are resiliently urged against a series of retaining members, comprising depressing the stack inwardly out of contact with the retaining members by seizing pressure between the end label of the stack and a pick-up surface that is divided along a straight line in its surface and, while the stack is so depressed and the label seized by the surface, pivoting at least one portion of the pick-up surface about an axis coincident with said line so as to withdraw at least one edge of the end label from the magazine, a relative movement then being brought about between the pick-up surface and the magazine to cause the pick-up surface to remove the label seized by that surface from the magazine.

6. Method as in claim 5, wherein suction is applied to the pick-up surface to seize the label.

7. A machine for labelling bottles or other cylindrical articles, comprising a conveyor adapted to receive the articles in definite spaced relationship, a magazine for containing a stack of labels, means for resiliently urging the stack towards a series of retaining members in the mouth of the magazine, a rotatable pick-up member adapted to seize the end label in the stack, the pick-up member being divided along a straight line in its operative surface, means for causing a relative movement between the pick-up member and the magazine so as to cause engagement between the pick-up member and the stack by which the stack is depressed inwardly out of contact with the retaining members, means for pivoting at least one portion of the pick-up member about an axis coincident with said line after the seizing action and while the stack is so depressed so as to withdraw at least one edge of the label from the magazine, means for intermittently rotating the pick-up member in timed relationship with the conveyor so as to carry the label towards a label-applying station adjacent the conveyor, means for rendering the label adhesive while it is held by the pick-up member, and means for causing the label to be transferred to an article on the conveyor.

8. A machine as in claim 7, comprising suction apertures in the operative face of the pick-up member, and means for applying suction to the apertures so as to cause the pick-up member to seize the label by suction.

9. A machine as in claim 8 wherein the pick-up member is adapted to remain stationary during the depression of the stack, the relative movement being brought about by moving the magazine toward the pick-up member, and wherein both portions of the pick-up member are adapted to pivot simultaneously about said axis.

10. A machine as in claim 7, comprising a se-

ries of pick-up members mounted on a common support arranged for intermittent rotation to carry the pick-up members in succession through label-feeding, gumming and labelling stations, each pick-up member having both portions arranged for simultaneous pivotal movement about their dividing line, means for applying suction individually to the portions of the pick-up members, means for rolling the successive articles along the gummed labels held by the successive pick-up members at the label-applying station, means for cutting off the suction applied to those portions of the pick-up members first encountered by the articles as those portions closely approach the label-applying station, and means for applying compressed air to those portions as the articles are rolled along the labels.
